UNITED STATES PATENT OFFICE.

FRANKLIN CHATFIELD, OF MINNEAPOLIS, MINNESOTA, ASSIGNOR TO NORTHWESTERN
KNITTING COMPANY, OF MINNEAPOLIS, MINNESOTA, A CORPORATION.

MEASURING DEVICE.

1,120,689.

Specification of Letters Patent. Patented Dec. 15, 1914.

Application filed September 7, 1912. Serial No. 719,247.

To all whom it may concern:

Be it known that I, FRANKLIN CHATFIELD, a citizen of the United States, and resident of Minneapolis, in the county of Hennepin 5 and State of Minnesota, have invented certain Improvements in Measuring Devices, of which the following is a specification.

This invention relates to improvements in devices designed particularly for measuring 10 strips of ribbon, tape, or other similar articles.

The object of the invention is to provide a device adapted particularly for use in factories where rolls of ribbon, tape or similar 15 articles are to be cut into pieces of uniform or substantially uniform length, and the object of the invention is to provide a device by means of which such strips can be quickly and expeditiously measured so as to permit 20 the operator to cut the same into pieces of uniform, or substantially uniform length.

In the accompanying drawings forming part of this specification, Figure 1 is a front elevation and Fig. 2 a side elevation of a 25 measuring device embodying my invention.

In the drawings, 2 represents a suitable base having a standard 3 rising therefrom and preferably formed integrally therewith. 4 represents a rod of any suitable or desired 30 length mounted in the standard 3 and secured therein by a suitable set-screw 5. This rod may be of any suitable length. In practice I prefer to make it about four feet long.

A suitable frame 6 preferably formed of 35 cast metal is mounted upon the rod 4 with its lower end preferably resting on the top of the standard 3, and it may be clamped in position by means of a set-screw 7. The lower portion of the frame 6 projects horizontally 40 from the top of the standard 3 and is provided with a substantially vertical slot 8, and the ribbon or tape A to be measured passes from a suitable reel and reel support (not shown) through the vertical slot 45 8 by which it is guided and kept in a flat position.

Upon the upper horizontal portion of the frame 6 is a U-shaped plate 9, which is mounted on said horizontal portion of the 50 frame and is secured in position by a set-screw 10. The guide 9 is provided near the end of each of its arms with a slot 11 and through these slots the ribbon or tape A passes.

55 A hand lever 12 is pivoted upon the frame

6. This lever is substantially L-shaped and is provided near its free ends with a marking point 13. A spring 14 engages the lever at the base of the device and normally holds said lever in a retracted position as shown 60 in full lines in Fig. 2. An inking roller 15 is mounted upon a pivoted arm 16 by means of a spring 17. The arm 16 is provided with a bell crank arm 18 and a spring 19 engages the end of the arm 18 and a lug 20 65 on a stationary part of the machine. A set-screw 21 is provided in the arm 16 which is adapted to bear against the rear of the lever 12 and holds the point 13 against the inking roller 15. The upright rod 4 is provided 70 with a series of notches 22 and these notches are suitably numbered. A sliding block 23 is mounted on the rod 4 and is provided with a spring 24 adapted to engage any one of the notches in the rod 4 and to lock said block 23 in position thereon. This block has an arm 25 provided with an opening 26 through which the tape or ribbon may pass and forms an adjustable guide on the graduated rod through which the free end of the 75 tape is inserted. A set-screw 27 is provided for holding said block in its desired position on said rod 4. The notches on the bar 4 will preferably be numbered to indicate in inches the desired lengths of ribbon or tape 80 85 to be secured by the use of this device.

Starting with the block 23 adjusted to the desired position the operator takes hold of the free end of ribbon or tape which passes through the opening 26 in the arm 25 and 90 draws down the end of said ribbon or tape until it is opposite or substantially opposite the screw 10 on the frame 6. He then presses down upon the lever 12 and this causes the point 13 upon said lever, against 95 which the inking pad has been resting, to move forward under said inking pad, which is then lifted from the full lines position shown in Fig. 2 to the dotted lines position 100 in the same figure, and the further downward movement of the handle end of said lever causes the inked face of the point 13 to strike against the face of the ribbon or tape between the two guideholes 11, 11. The ribbon is pressed against a rubber or other suitable plate 28 secured in an opening in the frame 6 opposite the inking roller and a suitable mark is thereby made on the face of the ribbon or tape. The operator then 105 pulls down the loose end of the tape draw- 110

ing the tape upward through the guides 8, 11, 11, and through the hole 26 of the arm 25, until the mark on the tape is substantially opposite the screw 10. (See Fig. 2.) 5 The operator can, with a shears or other suitable instrument, cut the ribbon or tape on mark previously made. This operation is repeated as often as desired. The piece of ribbon or tape cut off at each operation 10 will in length be equal to twice the distance from the screw 10 to the slot or opening 26 in the arm 25, and this slot or opening is opposite the notch on the rod that is engaged by the spring 24 (see Fig. 1). By this operation the lengths of ribbon or tape will 15 be cut off all of substantially the same length. To vary the lengths of the strips of ribbon or tape the block 23 may be adjusted up or down on the rod 4, thereby increasing or decreasing the length of a strip 20 of ribbon cut from the reel at each operation.

The details of the structure may be varied in many particulars without departing from 25 my invention.

I claim—

1. The combination, in a device for measuring tape or similar articles, with a base, of a rod mounted thereon, a stationary guide 30 through which the tape to be measured is fed, an adjustable block carried by said rod and forming a movable guide and adapted to receive the free end of the tape, and a marking device mounted near said stationary guide and means to operate the marking device to mark the tape when a predetermined length has been drawn through said guides.

2. The combination, in a device for measuring 40 tape and similar articles, with a base, of a rod mounted thereon, a stationary guide supported near one end of said rod, a second guide carried by the opposite end

of said rod and through which guides the tape to be marked is fed, the free end of the 45 tape being drawn through said second guide and carried back to a predetermined point near said first named guide, and a pivoted marking device mounted to mark the tape near said first named guide. 50

3. The combination, in a device for measuring tape and similar articles, with a suitable base, of a rod secured to said base in an upright position, and provided with a series of numbered notches, a frame through 55 which the tape is fed secured to said rod above said base, a guide carried by said frame, a pivoted marking arm arranged upon said guide and adapted to mark the tape in proximity to said guide, an adjustable guide upon said rod, and adapted to receive the free end of the tape and means for locking said guide in any desired position on said rod, substantially as described. 60

4. The combination, in a device for measuring tape and similar articles, with a suitable base, of a graduated rod mounted thereon, a stationary guide positioned near one end of said rod, an adjustable guide carried by said rod and through which guides the 70 tape to be marked is fed, the free end of the tape being drawn through said adjustable guide and carried back to a predetermined point near said stationary guide, and a marking device having an indicating 75 means and an operating handle disposed adjacent to said rod for marking the tape when a predetermined length has been drawn through said guides.

In witness whereof, I have hereunto set 80 my hand this 3rd day of September, 1912.

FRANKLIN CHATFIELD.
